Primary Examiner — Austin Murphy(57) **CLAIM**

I claim the ornamental design for an interactive learning pen, as shown and described.

DESCRIPTION

FIG. 1 is an upper right front perspective view of an interactive learning pen showing my new design;
 FIG. 2 is a front elevational view thereof;
 FIG. 3 is a left side elevational view thereof, the right side being a mirror image;
 FIG. 4 is a rear elevational view thereof;
 FIG. 5 is a top plan view thereof; and,
 FIG. 6 is a bottom plan view thereof.

1 Claim, 2 Drawing Sheets**FIG. 1****FIG. 5****FIG. 6**FIG. 2

FIG. 3

FIG. 4
